ELECTRICAL TRANSMISSION

Application filed September 17, 1936. Serial No. 136,174.

This invention relates to the transmission and distribution of electric currents and voltages and more particularly to the supply of energizing current and voltage to each stage 5 in a multi-stage amplifier of the space current type.

Some of the objects of the present invention are to conveniently and efficiently control the transmission of electrical energy to a 10 plurality of amplifiers of the space current type arranged in tandem; to provide a self contained unit for supplying a plurality of different space currents and a plurality of different grid or control element voltages for 15 different stages in a multi-stage amplifier; to reduce the distortion of waves transmitted by a multi-stage amplifier; and generally to provide apparatus adapted for adjustment to improve the transmission characteristic of a 20 multi-stage amplifier and to indicate the degree of distortion taking place therein.

In the species of the invention chosen for the purposes of illustration, a rectifier of 25 alternating current is associated with a wave suppression filter having a positive and negative output terminal, a bank of voltage control resistances being associated with the positive terminal of the filter for supplying space currents to the different stages of a 30 multi-stage amplifier, while a different bank of voltage control resistances is so related to a main resistance unit connected with the negative terminal of the filter as to control the respective grid or control element voltages 35 for the different stages of the amplifier. The main resistance unit provides a path in common for the space current for all of the tubes and is connected with all of the cathodes of the tubes.

40 An indicator connected between the filter and the banks of resistances serves to indicate the degree of distortion taking place while the waves are being amplified, the circuits being adapted for adjustment during operation 45 so that the distortion taking place in the amplifier may be minimized. The transmission characteristic of the amplifier is further improved by providing a bank of condensers in association with each bank of resistances, the capacity of the condenser asso-

ciated with the positive space current terminal of the last stage of the amplifier being larger than that of the other condensers in the same bank.

These and other objects and features of 55 the invention will be understood more clearly from the following description and the accompanying drawing.

The figure in the drawing shows a circuit diagram of a rectifier unit having current 60 and voltage distributing terminals connected with a multi-stage amplifier.

The alternating current generator 1 or other suitable source of alternating current is connected with transformer 2 by switch 3, the secondary winding of the transformer being provided with voltage taps 4 which permit of obtaining the desired output voltage. The output conductors 5 of the transformer supply alternating current power to the input terminals 6 of the rectifier network 7 of the full wave rectifying type made up of rectifier cells 8 poled in such direction that the current flows therethrough only as indicated by the arrows. The switch 9, in upper conductor 5, may be opened to include the variable resistance 10 therein for controlling the alternating current transmitted to the rectifier. The circuit illustrated is adapted for using electrolytic rectifier cells which have their most efficient voltage rating below that of the current to be rectified. By placing two or more of such rectifiers in series so that the sum of their rated voltages approximates the voltage to be rectified, it has been found that suitable operation takes place, whereas when a single rectifier is subjected to the full voltage, the rectifier deteriorates rapidly and the rectifying operation fails or is erratic. 75 80 85

90 The output conductors 11 of the rectifier are connected with the filter 12 consisting of the choke coil 13 in series with the upper conductor 11 and the condensers 14 and 15 connected in shunt with the conductors 11 at the opposite terminals, respectively, of the choke coil 13. The inductance of the choke coil should be large, for example, of the order of 100 henries, or some other suitable value. The filtered direct current is transmitted to the positive terminal 16 and the negative ter- 95 100

55 minal 17 of filter 12, the current transmitted to terminal 16 being transmitted through ammeter 19 which is normally short circuited by switch 18.

5 A main resistance unit 20 connected at one end with the negative terminal 17 has a space current return terminal 21.

10 A bank of resistance units 22' has a common connection with the positive terminal 16. These resistance units are preferably variable, but for the purpose of simplification may be made fixed. In many instances it has been found satisfactory to make all but one of the units fixed in value and the remaining unit variable to provide an adjustable detector voltage. Each unit has a free terminal 22, 23, 24, 25 and 26, respectively, these terminals providing positive potential connections for different stages of a multi-stage amplifier or for different circuits requiring independent voltages.

15 When employed for supplying space current to a multi-stage amplifier, the resistance units connected with terminals 22, 23, 24, 25 and 26 preferably have successively higher resistance values, so that the potentials of these terminals, when connected with proper anode circuits, are graded in value from a high voltage to a low voltage in the order of 20 the terminals named. For example, in a particular instance, a convenient series of voltages for certain purposes was found to be 135 volts for terminal 22, 90 volts for terminal 23, 67 volts for terminal 24, 45 volts for terminal 25, and a variable lower voltage for terminal 26. It is to be understood, however, that the invention is not restricted to these particular values.

25 A bank of condensers 27 has a common connection with terminal 21 of resistance 20, each condenser having a free terminal connected with a separate one of the positive terminals 22, 23, 24, 25 and 26, respectively. Condenser 28, connected with the highest voltage terminal 22, preferably has a much larger capacity than the other condensers in the bank, for example, of the order of 30 microfarads as compared with one-half a microfarad for each of the other condensers when used in 30 connection with low power tubes. Condenser 28 may conveniently be an electrolytic condenser.

35 A bank of resistance units 29 has a common connection with terminal 17 of the main resistance unit 20, this terminal being rendered negative by the drop of voltage therein when current is transmitted therethrough to a connected amplifier. Each resistance unit in bank 29 has a free terminal 30, 31 and 32, respectively, for separately transmitting and controlling an auxiliary or grid voltage for each of a plurality of repeaters or amplifiers, as in a multi-stage amplifier. These resistance units are preferably variable, but 40 may for the purpose of simplification be fixed

45 in value. Preferably, however, at least one variable unit should be provided when fixed units are employed elsewhere in the bank. The resistances are preferably so adjusted or chosen in value when connected with the 50 control elements or grids of a multi-stage amplifier that higher polarizing voltages are applied to the grids of the latter stages of the amplifier than to the first stages thereof. That is, terminal 30 may be more negative than terminal 31, which in turn is more negative than terminal 32 relatively to common 55 terminal 21. In order to accomplish this result the resistance of the unit connected with terminal 30 is less than that of the unit connected with terminal 31, which in turn is less than that of the unit connected with terminal 32. In the particular instance mentioned above wherein terminal 22 had a voltage of 135 volts, terminal 32 was 4 volts negative, terminal 31 was 9 volts negative and terminal 30 was adjustable to a still more negative voltage adapted for the grid of a power tube in the last stage.

60 A bank of condensers 33 has a common connection with the free terminal 21 of resistance unit 20, each condenser having a free terminal connected respectively with a separate one of the negative terminals 30, 31 and 32, respectively. Condensers 33 may be of 65 relatively low capacity, for example, where a circuit is to be employed with low power tubes, these condensers may each have a capacity of the order of one half a microfarad.

70 All of the elements described above and numbered 1 to 33, inclusive, are preferably assembled together as a self contained compact combination, hereinafter called a rectifier unit or an electric supply unit, adapted 75 by its terminals 22 to 26 and 30, 31, 32, for quick and convenient connection with amplifiers or other loads.

80 In the circuit shown, a multi-stage repeater or amplifier 34 adapted for use as a radio receiver, includes the successive stages 35, 36, 37, 38, 39 and 40, respectively, which may be of the space current type, each having 85 an anode 41 and a filamentary cathode 42 and a grid or control element 43. Tubes 35, 36 and 37 serve as radio or high frequency amplifiers, tube 38 serving as a detector, while tubes 39 and 40 serve as audio or low frequency amplifiers.

90 All of the cathodes 42 are connected together with the ground 47, and with the negative terminal 21 of the rectifier unit by conductors 48 and 49. The cathodes or filaments of the tubes 35, 36, 37, 39 and 40 are heated from current from battery 44 under the control of rheostat 45, the filament of 95 detector tube 38 being supplied by battery 44 and controlled by rheostat 46.

100 The anodes 41 of the first two amplifier stages 35 and 36 are connected with terminal 105 25 which is adapted to supply the lowest 110

amplifier voltage. The anode of amplifier 37 is connected with terminal 24 which supplies a voltage somewhat higher than that of terminal 25, and the anode of detector tube 38 is connected with terminal 26 which normally is the lowest voltage terminal in connection with bank 22 and which is preferably adjustable to provide the most desirable detector voltage. The anode of audio or low frequency amplifier 39 is connected with terminal 23 which supplies a voltage somewhat higher than that of terminal 24, the anode of amplifier 40 being connected with terminal 22 which supplies the highest voltage.

15 The grids 43 of amplifiers 35 and 36 are connected with conductor 49 and terminal 21 which is common to the cathodes of the tubes so that the normal potentials of these grids are the same as that of the negative terminal 20 of the filaments 42. The grid of amplifier 37 is connected with negative terminal 32 which supplies a small negative polarizing voltage thereto, the grid of detector 38 being connected with conductor 49 and terminal 25 21, so that the potential of the grid is the same as that of the negative terminal of the filament. The grid of amplifier 39 is connected with terminal 31 which supplies a negative polarizing potential to the grid of higher 30 value than that applied to amplifier 37, the grid of power amplifier tube 40 being connected with negative terminal 30 which supplies a suitably high polarizing potential to the grid by adjusting the variable resistance connected with terminal 30. It will thus be seen that successive amplifying stages are supplied with successively higher positive space current voltages from the terminals 22, 23, 24, 25 and 26, respectively, while the 40 grids in successive amplifying stages are supplied with successively higher negative polarizing potentials relatively to the cathodes.

Radio or other carrier waves modulated in accordance with signals or speech are transmitted to the input terminals 50 of a multi-stage amplifier circuit by way of antenna 51 and ground 47 or other suitable means. The primary winding of input transformer 52 is connected with terminals 50 and includes a 50 condenser 53 in circuit therewith for tuning to waves to be received. Variable condenser 54, in shunt with the secondary winding of transformer 52, permits of tuning the input circuit of amplifier 35 to the waves of desired 55 frequency, the amplified waves being transmitted to the primary winding of transformer 55, the secondary winding of which is shunted by variable condenser 56 for tuning the input circuit of amplifier 36 to the same frequency as that of amplifier 35. Similarly 60 transformers 57 and 58 shunted respectively by means of variable condensers 59 and 60 are tuned to the same frequency, so that the desired waves are amplified in the first three 65 stages and transmitted to the grid of de-

tector 38. The detected waves in the anode circuit of detector 38 of audible or low frequency, are transmitted successively through low frequency coupling transformers 61 and 62 and low frequency amplifiers 39 and 40 to the loud speaking receiver or other suitable responsive device 63.

Before starting the electrolytic rectifier for the first time, the upper conductor 5 is connected with the lowest voltage tap 4, and switch 9 is opened to include variable resistance 10 in the output circuit 5 of transformer 2, the resistance being adjusted to maximum value before applying current from source 1 to the primary winding of the transformer. 80 Switch 3 is then closed to connect source 1 with transformer 2 which transmits current to rectifier 7 to form a suitable film on the electrodes therein, resistance 10 being gradually cut out as the film forms thereon and until a suitable direct current voltage is transmitted to the output conductors 11 of the rectifier. In case the rectified voltage is insufficient when all of the resistance 10 is cut out, the upper conductor 5 is connected with one of the higher voltage taps 4 of the transformer and, in case the desired voltage is between two taps, connection is made with the one of higher voltage, switch 9 being kept open and resistance 10 being adjusted to such a value that the effective voltage applied to the rectifier is between the voltages of the two taps. It is thus possible to obtain any desired voltage with a relatively small number of taps of the transformer and with a relatively small resistance in series with the transformer output conductors, so that regulation of the circuit approaches that obtainable by a direct connection with a special tap between those actually provided.

100 Owing to the high electrostatic capacity of the electrolytic rectifier cells 8 and the wave suppressing effect of the filter network 12, the voltage supplied to terminals 16 and 17 is substantially free from undesirable wave components.

The total current supplied to amplifier circuit 34 from the rectifier may be read directly on ammeter 19, by pressing key 18.

115 In general, the arbitrary adjustment of the positive potentials of terminals 22 to 26, inclusive, in conjunction with the negative potentials of terminals 30, 31 and 32, results in appreciable distortion of the wave being amplified, owing to departures of the operating 120 characteristics of the tubes from the assumed values and the fact that the tubes do not operate on the most linear portions of their amplifying characteristics. The effect of the resulting distortion is to undesirably mutilate the waves transmitted from the amplifier and to produce distorted sounds in receiver 125 63. Another effect is to change the space current supplied to the amplifiers so that, when waves of constant amplitude are being ampli- 130

fied, a fairly constant change of deflection may be noted on ammeter 19 with key 18 open, the degree of distortion being continuously indicated by the amount of deflection of the ammeter, as read on its calibrated scale.

When a high frequency wave is being amplified and the amplitude varies, a variable amount of direct current is transmitted through ammeter 19. When the variations of 10 amplitude of the high frequency wave are rapid, the deflection of the ammeter is seemingly constant, owing to its failure to respond to the rapid changes of current, but when the rate of change of amplitude of the high frequency wave is low, that is, a few cycles each 15 second, the effect may be readily observed on the ammeter.

In order to adjust the voltages supplied to the amplifier stages to suitable values to 20 minimize distortion and to insure operation near the best part of the most linear portion of the characteristic of each stage, switch 64 and key 65 may be closed to apply a high frequency wave from source 66 to the primary 25 winding of transformer 67, the secondary winding of which is connected through switch 64 with the input terminals 50 of the receiving circuit. When one or more of the tubes are so adjusted as to distort, the closure of 30 key 65 causes a change in the direct current transmitted through ammeter 19, power tube 40 producing the greatest change, while low frequency amplifier 39 and the prior amplifier stages produce smaller changes when out 35 of adjustment.

By adjusting the resistance connected with terminal 30, the negative polarizing voltage supplied to the grid of power tube 40 may be varied until the distortion produced in 40 the tube is reduced to a minimum as indicated by the change of deflection of ammeter 19. While the amount of distortion may be more conveniently adjusted for many purposes by means of variations in the resistance connected with terminal 30, it is within 45 the scope of the present invention to adjust the resistance connected with the positive space current terminal 22, either in conjunction with or independently of an adjustment 50 of the resistance in the grid circuit. In some cases, where the observable distortion is very slight, the grid voltage may be adjusted first to an extreme distorting value on one side of the minimum distorting value and then 55 to an equally distorting value on the opposite side of the minimum, the adjustment for minimum distortion being then located between these extremes. It will be noted that 60 the change of deflection of the ammeter, produced by distortion in a repeater tube, is made apparent by intermittent closure of key 65.

After adjusting the distortion of amplifier 65 to a minimum or negligible value, the next prior amplifying stage including tube 39, may

be adjusted to the most linear working portion of its amplifying characteristic, the next prior stages being successively adjusted in the inverse order of their sequence in the amplifier. Switch 64 may then be opened 70 and keys 18 and 65 restored to normal so that the amplifier may then operate with a minimum of distortion. While adjusting the distortion to a minimum, the effect on ammeter 19 of distortion in detector 38 may be avoided 75 by energizing the anode circuit of the detector from a source of space current separate from the electric supply unit.

The condensers in banks 27 and 33 improve 80 the quality of transmission of the amplified waves and provide paths of suitably low impedance for the alternating components of the current transmitted to and from the amplifier and detector tubes. Furthermore, each condenser in combination with the resistance unit associated therewith forms a filter section supplementing the effect of filter 12 in suppressing alternating components of current from rectifier 7. By making condenser 28 of extra large capacity, the impedance thereof is very small or negligible 85 in relation to the impedance of the output circuit connected with power amplifier 40 or the last stage of the amplifier with which the condenser is connected. 90

I claim:

In a space current supply system, a direct current source having a positive terminal and a negative terminal, a bank of resistance units having a common connection with the positive terminal for separately controlling the voltages at said resistance units, a space current return terminal, a main resistance unit connected between the negative terminal of the direct current source and the space current return terminal, and an additional bank of resistance units having a common terminal connected to the negative terminal of the direct current source, each unit in said additional bank being separate from the other units in said bank except at said common terminal, and each having a free terminal for separately controlling an auxiliary potential. 105

In witness whereof I hereunto subscribe 110 my name this 26th day of August, 1926.

LOUIS C. BILLOTTE.
